UNITED STATES PATENT OFFICE

159,216

STOCKING

Otto E. Kuehnert, Selinsgrove, Pa., assignor of one-half to Nellie Kuehnert, Selinsgrove, Pa.

Application August 3, 1948, Serial No. 147,903

Term of patent 3½ years

(Cl. D47—7)

To all whom it may concern:

Be it known that I, Otto E. Kuehnert, a citizen of the United States, residing at Selinsgrove, in the county of Snyder and State of Pennsylvania, have invented a new, original, and ornamental Design for a Stocking, of which the following is a specification, reference being had to the accompanying drawing, forming part thereof.

I claim:

The ornamental design for a stocking, as shown.

OTTO E. KUEHNERT.
